UNITED STATES PATENT OFFICE.

JOHN C. SCHAFER, OF MCKEESPORT, PENNSYLVANIA.

METALLIC TIE.

No. 841,899.

Specification of Letters Patent.

Patented Jan. 22, 1907.

Application filed March 14, 1906. Serial No. 306,010.

To all whom it may concern:

Be it known that I, JOHN C. SCHAFER, a citizen of the United States of America, residing at McKeesport, in the county of Allegheny and State of Pennsylvania, have invented certain new and useful Improvements in Metallic Ties, of which the following is a specification, reference being had therein to the accompanying drawings.

10 This invention relates to certain new and useful improvements in metallic ties; and the invention has for its primary object to provide a strong and durable metallic tie having a simple and inexpensive rail-fastener.

15 Another object of this invention is to provide a metallic tie which can be easily tamped and embodied in the road-bed or ballast of a railroad or street-railway, whereby the rails secured to said ties will be firmly supported 20 and prevented from spreading or becoming displaced.

Briefly described, my improved metallic ties are constructed of strong and durable metal in the form of channel-bars, the ties being 25 provided with concave bases to engage in the ballast of a road-bed, and they are flanged to support rails, the flanges of said ties being cut or sheared and bent to form lugs which are adapted to engage the base-flanges of 30 rails and retain said rails in engagement with the ties.

The detail construction of my improved metallic ties will be hereinafter more fully described and claimed, and, referring to the 35 drawings accompanying this application, like numerals of reference designate corresponding parts throughout the several views, in which—

Figure 1 is a perspective view of a number 40 of ties constructed in accordance with my invention, said view illustrating a section of the track. Fig. 2 is a plan of one end of a tie, and Fig. 3 is a cross-sectional view of the same.

45 To put my invention into practice, I construct my improved ties of channel-bars 1, said bars being cut into the desired lengths common to railroad-tracks. The channel-bars 1 embody curved bases 2, side walls 3, and outwardly-extending flanges 4 and 5. The curved base 2 of each channel-bar is provided with rounded edges 6 to facilitate the tamping of the channel-bar upon a road-bed. The inner or confronting sides of the 55 walls 3 of each bar taper inwardly, as at 7, to strengthen the side walls and form a

substantial tie. The outwardly-extending flanges 4 and 5 of each bar are cut and sheared, as at 8, to form lugs 9 and 10, said lugs being bent upwardly to engage the base-flanges 11 and 12 of rails 14, mounted upon the flanges 4 and 5 of the ties. By referring to Figs. 2 and 3 of the drawings it will be observed that the flange 5 is cut and sheared the reverse of the flange 4, whereby the lugs 9 and 10 will extend inwardly toward one another, thereby providing a lug upon each flange which will engage the base-flanges 11 and 12 of the rails 14 and firmly hold the rails in engagement with the ties when the ties are properly positioned in parallel alignment with one another.

In order to secure the rails to the flanges 4 and 5 of the ties, it is necessary in placing a tie in engagement with a rail to swing the 75 same at an angle to the rail in order that the lugs 9 and 10 may be placed in engagement with the flanges 11 and 12 of said rails. After the lugs have engaged the edges of the flanges the ties can be swung at right angles 80 to the rails, thereby firmly locking said rails upon the ties.

The flanges 4 and 5 of the ties are provided with openings 15, whereby guard-rails, switch construction, and signal mechanism may be secured to the ties.

My invention resides entirely in the detail construction of the channel-bars 1, which I use as ties, and such changes in the construction of the ties as are permissible by the appended claims may be resorted to without departing from the spirit and scope of the invention.

What I claim, and desire to secure by Letters Patent, is—

95 1. A railroad-tie consisting of a single straight piece of metal, having at each end a pair of integral lugs overhanging the top surface of the tie, the two lugs of each pair being arranged to project inwardly toward each other and being spaced on the tie so as to be on opposite sides of the tie and also on opposite sides of the rail-seat, said tie being adapted to be applied to the rail by being first adjusted obliquely to receive the full width of the rail between the lugs and then be turned to cause said lugs to overhang and lock down the rail-flanges as described.

2. A railroad-tie consisting of a single straight piece of metal having struck up 110 from its body-plate at each end a pair of integral obliquely-arranged overhanging lugs,

the lugs of each pair projecting toward each other as described.

3. A railroad-tie consisting of a single straight piece of metal having integral locking devices at opposite ends forming a unitary tie and lock adapted to hold the rail by a deflection of the tie without spikes, bolts or other separable parts, as described.

4. A metallic tie consisting of a channel-bar having a curved base, side walls, outwardly-extending flanges carried by said

side walls, and integral obliquely-arranged overhanging lugs struck up from said flanges, the lug on one flange projecting toward the lug on the opposite flange. ¹⁵

In testimony whereof I affix my signature in the presence of two witnesses.

JOHN C. SCHAFER.
